METHOD OF PRODUCING MOCK
PATCH POCKETSIsidor J. Herman and Alexander D. Davis,
Montreal, Quebec, CanadaApplication November 7, 1945, Serial No. 627,139
In Canada October 17, 1945

4 Claims. (Cl. 2—247)

1

This invention relates to the formation of a part of a piece of material to simulate a separate patch applied to the material, and is directed specifically to a mock patch pocket having a facing which is an integral part of the adjacent material but gives the appearance of being the separate patch of a patch pocket.

Patch pockets, which are much in demand, are relatively expensive to make because they require more material than the ordinary pocket and more time is involved in their making. In the tailoring of a suit coat, for example, having a patch pocket it is necessary to cut a piece of the suiting of a size sufficient to allow the formation of a pocket which will match the rest of the coat. The patch must be carefully positioned and in the case of patterned material the design must be matched.

It is customary in modern methods of making clothing to have the various parts of the garment made by different workers and this means that the various parts must all be numbered. Thus the worker whose duty it is to apply to a garment a patch pocket cut by another worker has to compare the numbers on the two parts in addition to carefully positioning the patch and matching the design as mentioned above.

An object of the present invention is to provide a mock patch pocket which does not require the use of an extra patch of material and, therefore, does not require the matching of numbers and designs referred to above.

More particularly, an object of the present invention is to so form a pocket facing which is an integral part of the adjacent material of a garment that it has the appearance of being a separate patch.

Another more broad object of the invention is to so form part of a piece of material as to simulate a separate patch applied to the material.

Other objects and features of the invention will appear from the following description with reference to the drawings in which

Figure 1 is a plan view of one type of mock patch pocket according to the invention.

Figure 2 is a plan view showing the pocket area of a garment after it has been slit and the outline of the pocket has been stitched.

Figure 3 is a section on the line 3—3 of Figure 1.

Figure 4 is a partial section on the line 4—4 of Figure 2.

Figure 5 is a detail view illustrating the stitching of the folded material close to the fold line, and

Figure 6 is a partial section on the line 6—6 of Figure 1.

2

The first step in forming a mock patch pocket according to the invention on a suit coat for example, is to slit the suiting 10 on the line 11 shown in Figure 2 substantially parallel to the intended top line of the pocket. A short slit 12 is then made on either side of the slit 11 at each end thereof.

If the pocket is to be of the type shown in Figure 1 a strip 13 of the suiting material is then connected to the suiting 10 at the top of the slit 11 and a welt 14 is connected to the suiting material 10 at the bottom of the slit 11. Two pieces of lining material 15 and 16 are then connected respectively to the welt 14 and to the lining strip 13. As shown in Figure 3 the welt is double and its two free edges are connected by a row of stitching 17 through the suiting 10, the two thicknesses of the welt 14 and the lining 15. The lining 16 is conveniently connected to the bottom edge of the lining strip 13 by the row of stitching 18 and is then doubled over the back face of the lining strip 13 and connected through it near its top edge to the suiting 10 by a row of stitching 19. It will be understood that the connection of the lining strip 13 and welt 14 to the suiting 10 and the connection of the lining 15 and 16 to the suiting 10, strip 13 and welt 14 form no part of the present invention, the form of these connections being variable according to the form of finishing used for the top of the pocket.

To form the mock patch pocket, the next step after cutting the slits 11 and 12 is to place a pattern in position on the suiting 10 and chalk-mark the outline of the bottom and sides of the pocket. Then the suiting 10 and the linings 15 and 16 are stitched together on the chalk line 20, the result being that shown in Figure 4. Then the suiting 10 is folded back from the reverse side of the material so far as the stitching on the line 20 will permit, and then the worker stitches through the two folded thicknesses of suiting 10 and through the two pieces of lining material 15 and 16 at 21 which, as shown in Figure 5, is close to the stitched line 20. As indicated by the dotted lines in Figure 5 the suiting 10 is then folded back again around the stitching 21 to the position shown in Figure 6. The two edges of lining material 15 and 16 are also folded back around the stitching 21 and the operator stitches through the suiting 10 and four thicknesses of lining material as shown at 22.

The result is that the facing is defined by two folds of material, the fold which is directed away from the reverse side of the material being stitched close to the fold line so that the edge of

the facing as seen in Figure 1 stands up from the adjacent suiting material 10 and makes the facing look like a separate patch. This appearance is enhanced by the line 22 which of course, may be spaced inwardly from the edge of the pocket to any desired extent.

It will be apparent that the result of proceeding as set forth above is to take up a certain amount of the suiting, and it might be thought necessary to form one or more darts above the pocket to dispose of the resulting fullness. This may be done, but it is desired to point out that it is not essential because the second stitch line is close to the first and therefore the amount of material taken up is very small.

Although the invention has been described with reference to a patch pocket of a particular type of trim and applied to a suit coat, it will be understood that the invention is applicable to any of the various forms of patch pocket trim, and to any type of material capable of being sewn.

What we claim as our invention is:

1. A method of forming part of a piece of material to simulate a separate patch applied to said material, comprising sewing a stitch line defining the desired outline, folding said material along said line away from the reverse side of said material, sewing from such reverse side a line of stitching alongside the first stitch line but through the two thicknesses of folded material and folding said material back again from the obverse side thereof along the second line of stitching.

2. A method of forming a pocket facing on a piece of material to simulate the separate patch of a patch pocket, comprising sewing a stitch line defining the desired outline of at least the bottom and sides of a pocket, folding said material along said line away from the reverse side of said material, sewing from such reverse side a line of stitching alongside the first stitch line but through the two thicknesses of folded material, folding said material back again from the obverse side thereof along the second line of stitching, and sewing a further line of stitching spaced inwardly from and approximately parallel to the first stitch line.

3. A method of forming a pocket on a piece of material to simulate a patch pocket, comprising slitting the material along a straight line parallel to the intended top edge of the pocket, sewing lining material to the top of the resulting slit, sew-

ing a stitch line defining the outline of the bottom and sides of a pocket through said material and through said lining, the portions of the line defining the sides of the pocket ending in the area of the ends of said slit, folding said material along said stitch line away from the reverse side of the said material, sewing, from such reverse side, a line of stitching through the folded two thicknesses of material and through said lining material close to the fold line, and folding said material back again from the obverse side thereof along the second line of stitching.

4. A method of forming a pocket on a piece of material to simulate a patch pocket, comprising slitting the material along a straight line parallel to the intended top edge of the pocket, sewing lining material to the top of the resulting slit, sewing a stitch line defining the outline of the bottom and sides of a pocket through said material and through said lining, the portions of the line defining the sides of the pocket ending in the area of the ends of said slit, folding said material along said stitch line away from the reverse side of the said material, sewing, from such reverse side, a line of stitching through the folded two thicknesses of material and through said lining material close to the fold line, and folding said material back again from the obverse side thereof along the second line of stitching, and sewing a further line of stitching spaced inwardly from and approximately parallel to the first stitch line from the obverse side of said material.
